United States Patent Office

Des. 211,767

Patented July 23, 1968

211,767

VANITY MIRROR

Harry Disko, Park Ridge, Ill., assignor to Marvin Glass
& Associates, Chicago, Ill., a partnership

Filed May 25, 1967, Ser. No. 7,266

Term of patent 14 years

(Cl. D86—10)

Fig 1

I claim:

The ornamental design for a vanity mirror, substantially as shown and described.
